APPARATUS FOR PRODUCING A COMPOSITE
REENFORCED SHEET

William R. Collings and Donald L. Gibb, Midland,
Mich., assignors to The Dow Chemical Company,
Midland, Mich., a Corporation of Michigan

Application March 19, 1930. Serial No. 436,936

17 Claims. (Cl. 154—1)

The present invention relates to paper reenforcing machines, and more particularly to that type of such machines wherein paper fabric is strengthened by means of crossed diagonally laid grouped fibres, yarn strands or threads of textile or other material.

Numerous attempts have heretofore been made to provide a machine which would assemble a composite reenforced sheet having diagonally laid reinforcing threads crossing each other in unwoven manner. Most common among such machines are those having a rotating spool creel and a rotating yarn guide for laying the yarn strands transversely of the fabric to be reenforced (Pember et al U. S. Patent No. 285,838). A still different type of machine used for a similar purpose (Howard U. S. Patent No. 1,211,851), has a stationary yarn creel which supplies yarn strands to a series of swinging arms that carry 10 the strands back and forth across the sheet to be reenforced, the yarn strands being hooked over pegs on carrier chains at opposite sides of the sheet, such chains moving horizontally in unison with the sheet and having pegs rising vertically 20 to receive the yarn and then carrying it past the squeezing rolls to a trimmer that cuts off the yarn loops at the edge of the paper. The first of these methods normally produces a reenforced sheet having the reenforcing strands laid with 25 non-uniform spacing and in curved paths which results in a product of non-uniform strength. The second type machine on the other hand is very complex in its movements as well as in the 30 method of hooking the reenforcing strands over pegs or the like on moving carriers, it being noted also that there is a certain loss of reenforcing material due to the trimming operation which follows.

Among the objects of the present invention is 40 the provision of a stationary creel type machine for producing a composite sheet reenforced in diamond like pattern with substantially parallel reenforcing strands laid diagonally in two layers one over the other in unwoven manner, such machine further applying the transverse reenforcing 45 yarn or threads directly to the adhesive coated face of one sheet where they are pressed into the surface of the adhesive layer prior to final assembly of the composite sheet. Other objects 50 and advantages will appear as the description proceeds.

To the accomplishment of the foregoing and related ends, the invention, then, consists of the steps and means hereinafter fully described and 55 particularly pointed out in the claims, the an-

nexed drawings and the following description setting forth in detail certain means and modes of carrying out the invention, such disclosed means and modes illustrating, however, but several of various ways in which the principle of the invention may be used.

In said annexed drawings:—

Fig. 1 is a diagrammatic general assembly view, in perspective, of a preferred form of our fabric reenforcing machine; Fig. 2 is a section of the 60 machine in the plane indicated by line 2—2 in Fig. 1; Fig. 3 is a longitudinal sectional view of the central portion of the machine shown in Fig. 1; Fig. 4 illustrates one type of reenforced sheet produced by the machine shown in Fig. 1; Fig. 5 70 illustrates a still different type of reenforced sheet which may be produced by the same machine.

In carrying the invention into practical effect, one of the component sheets of the material to be reenforced, which for convenience will be referred to as "paper", is taken from a roll or other supply and coated on one side with adhesive, preferably of pitch type which may be applied hot. The pitch coated sheet is then passed longitudinally through the reenforcing machine where the 75 reenforcing yarns, threads, cords, or the like, which for convenience will be hereinafter referred to as yarn, are taken from a source of supply and carried back and forth across the pitch coated 80 face of the longitudinally moving sheet. Each 85 of the so supplied yarn strands passes under a cross roller (one of a series), each said roller normally receiving not to exceed five yarns strands which it presses into the pitch layer where the 90 yarn is then held both adhesively and by subsequent cross rollers which it passes under. After 95 passing the yarn applying mechanism, the sheet now carrying the yarn strands in unwoven diamond pattern is brought into contact with a second sheet of paper coated with hot pitch and the whole, with adhesive coated faces adjacent, is passed through a squeezing device which seals them together into a composite reenforced sheet.

Referring more particularly to the drawings, 2 100 is a roll of paper adjustable endwise for lining up, said roll also being provided with any suitable tension device (not shown) to keep the paper tight while being drawn from the roll. The paper 1 passes from roll 2 to a group of three steam heated driven rolls 3, 4, and 5, 3 and 4 acting to feed the paper from supply roll 2 while roll 4 runs in contact with roll 5, which transfers adhesive thereto from tank 6, which also is steam heated to facilitate flow of adhesive, where the adhesive used becomes less viscous upon heating. 110

Sheet 1 having adhesive applied to one face, then passes into cooling chamber 7 with adhesive-coated face up. Cooling chamber 7 is supplied with a cooling medium, for instance air, supplied by means of a conveniently driven fan 8 through connecting pipe 9. Sheet 1, having its adhesive coating, for instance pitch, cooled to a point where it is substantially non-sticky to a rolling surface contacting therewith but sticky to yarn 5 pressed thereon passes under idler roll 10 with pitch-coated face in contact therewith. The sheet then passes between a series of approximately parallel rollers 11 and 12 (Fig. 3), which may be in a straight line as shown or on a curve, 10 and after leaving the same is brought in contact with pitch-coated sheet 13, passing around idler roll 14 so that its pitch-coated face coincides with that of sheet 1. Sheet 1, while passing between rollers 11 and 12 with pitch-coated face 15 up, has reenforcing yarns applied thereto in diamond like pattern in two diagonal layers, one above the other, in unwoven manner. Yarn from spools or other convenient supply 15 (Fig. 1) is drawn through a guide piece 16 containing guide 20 bushings 20 for guiding the yarn strands. The yarn then passes over roll 17 which may be an idler but is preferably driven in any convenient manner at a speed slightly in excess of the yarn speed. The yarn strands then pass through guide 25 eyelets 18 and 19 (Fig. 2) mounted on carriage 21, from whence the yarn passes under rolls 12 (Fig. 3), one yarn under each roll, which rolls press it into the pitch-coated face of sheet 1, 30 passing thereunder longitudinally of the machine. Carriage 21 is mounted on tracks or 35 guides 22 by means of suitable wheels or other means 23. It is thus seen that the carriage 21 is arranged to travel crosswise of the machine on guides 22. However, in order to correlate the 40 cross travel of carriage 21 in unison with the rate of travel of sheet 1, arm or bar 24 fastened in suitable manner to carriage 21 (Fig. 1) is connected at its free end to a suitable drive capable of making carriage 21 travel back and forth across sheet 45 1 in substantially uniform manner. This drive, for instance, may consist of a drive chain 25 having a suitable connection 26 between such chain and arm 24. By driving chain 25 at uniform speed the carriage 21 is caused to travel back 50 and forth at like speed due to its connection to chain 25 through arm 24 and connector 26, such travel preferably being slightly less than the width of the sheet being reenforced. It will thus be seen that where the reenforcing yarns are to 55 be laid at an angle of approximately 45° as shown in Figs. 4 and 5, it will only be necessary for the carriage 21 to make one complete trip across and back while paper sheet 1 is traveling a distance equal approximately to twice its width, it being 60 noted, of course, that the distance on the carriage from outside yarn to outside yarn should be approximately twice the width of the paper to be reenforced.

Sheet 13 is drawn from endwise adjustable supply roll 29 having a suitable tension device (not shown) to keep the paper tight while being drawn therefrom. Sheet 13 then passes to a group of three steam jacketed driven rolls 30, 31, and 32. Rolls 30 and 31 act to feed the paper from roll 29, 65 while roll 31 runs in contact with roll 32 which transfers adhesive (pitch) thereto from steam heated supply tank 33. Hot pitch-coated sheet 13 then passes around idler roll 14 which brings it in contact with sheet 1 carrying the diamond like pattern diagonally laid reenforcing yarn. 70

Pitch-coated sheets 13 and 1 (Fig. 3) with reinforcement therebetween then pass over a heater 40 where the cold pitch on sheet 1 is softened following which the whole is delivered to squeezing rollers 27 and 28 which seal them together 75 into a composite sheet. While this heater can be omitted from the machine we have found that its use, particularly when the surface in contact with the paper is ribbed spreader fashion to remove wrinkles from the under sheet, aids in producing 80 a uniform and satisfactory product. In order to make sheet 1, which is coated with pitch, a little more pliable so as to effect a better union when passing between squeezing rolls 27 and 28, it is 85 preferable to moisten the under side of sheet 1, for instance by applying water to roll 28 from water supply tank 34, by means of roll 35 which may be driven at the same peripheral speed as roll 28. The so assembled reenforced sheet leaves 90 squeezing rolls 27 and 28, which are driven in any suitable manner at the proper rate of speed, and passes to a point of usage, or if desired, to wind-up roll 36 which may be hand operated or power driven in any suitable manner. 95

Where the reenforced sheet is desired in the 100 form shown in Fig. 5 it is only necessary to insert an additional series of guide eyelets 37 directly in the path of travel of the series of guide eyelets 19, it being noted that the passage of a 105 yarn strand through guide eyelet 37 simultaneously with the passage of a similar yarn strand through guide eyelet 19, both of which deliver the yarn between the same pair of rollers, automatically forms the type of reinforcement shown in Fig. 5 which for convenience may be termed as 110 "reenforcement placed in shingle formation." The distance between guide eyelets 19 and 37 will determine the exposure or extent of step back in the shingle effect along the edge of the sheet. This type of construction is of special advantage 115 where the reenforced sheet is to be tubed with the shingled edges being brought together to form the seam of the tube. It further presents the advantage of enabling the yarn strands to be placed twice as close together as would be the 120 case with the same apparatus having only one series of guide eyelets, for instance 19. It is further to be noted that our invention is not limited to one or two strands placed in this manner but that several strands can be passed under 125 the same roller and make a corresponding number of steps in the shingle formation of the re-enforcing yarns. The back and forth motion of carriage 21 may be accomplished in a number of 130 different ways, one preferred form of which is illustrated. The carriage might be driven by means of a pair of chains, one for each side of the carriage, or in some cases it might even be satisfactory to accomplish the back and forth movement by means of a cam. It is to be noted 135 in this connection that if a quick return or change of direction of the yarn at the edge of the sheet being reenforced is desired, the sprockets 38 should be kept as small as possible. Since a uniform back and forth movement of the carriage together with a uniform feed of paper is necessary for the production of a uniform product we prefer to drive the entire apparatus from a single source of power, for instance by means of a suitable drive to pulley 39. 140

While we have shown sheet 1 as passing down inclined cooler 7 and under idler roll 10, we do not wish to be limited to that exact construction, since it is merely a matter of convenience whether such inclined passage is used or whether the pa- 145

per is passed in a straight line to and between rolls 11 and 12, and it is further to be noted that the paper may pass to rolls 11 and 12 from a lower elevation. Either the same level or lower elevation will make the use of roll 10 unnecessary. It is further to be noted that the reduction of stickiness of the adhesive may be accomplished by other means than circulating air through cooling chamber 7. For instance, by sufficiently increasing the span between rolls 3 and 10, the adhesive will be given time enough to dry or cool to the desired stickiness. After passing adhesive-coated sheet 1 between rolls 11 and 12 where the reenforcing yarn is applied, sheet 13 is brought into contact therewith and the whole passed between squeezing rolls 27 and 28, one of the rolls preferably being made with a soft or rubber covered surface which will squeeze the paper into intimate contact with the other sheet and form a good seal around the yarn strands and leave the opposite side of the sheet smooth for printing. In case it is not essential to have one side smooth for printing, both rolls may be made with rubber covered surfaces. However, to facilitate the squeezing, the back of sheet 1 is moistened to reduce its resiliency and tendency to pull away from the opposite sheet when the squeezing pressure (roll 28 being rubber covered) is removed. In some cases it may be desirable to moisten the back of sheet 13 or even the backs of both sheets 1 and 13 depending upon the conditions at hand. The moistening may be done by means of a wet roller, sprays or other moistening apparatus. Preferably where crepe paper is used the moistening should take place as close to the squeezing operation as possible to avoid stretching or removal of the crinkles in the paper. We accordingly prefer when using crepe paper to moisten it by direct application of water to squeezing roll 28 which immediately squeezes the sheets into a composite form.

While our machine has been described in terms of placing the reinforcing yarn strands at an angle of 45° from the edge, we do not wish to be limited to that exact form, since it is obvious to anyone skilled in the art that a change in ratio of speed of the paper through the apparatus to the carriage travel will change the angle. It is further to be noted in this connection that different widths of paper can be reenforced, it being only necessary to change the carriage travel so that it coincides with the width of the paper and at the same time supply the yarn in proper amount and number of strands to meet the new condition.

We further do not wish to be limited to applying pitch to both sheets since it would be obvious to anyone familiar with the art that the composite reenforced sheet could be formed by coating only one sheet with a suitable amount of pitch and then assembling and squeezing. We have further found it possible to lay the yarn strands in unwoven diamond pattern on a non-adhesive coated sheet passing through the machine, adhesive being subsequently applied together with a second sheet and the whole pressed into the desired form.

Other modes of applying the principle of our invention, may be employed instead of those explained, change being made as regards the means and steps herein disclosed, provided those stated by any of the following claims or their equivalent be employed.

We therefore particularly point out and distinctly claim as our invention:—

1. In a machine of the character described, the combination of means for feeding material

to be reenforced, reenforcing-strand-presenting means moving to and fro in a substantially straight line for taking a plurality of reenforcing strands from a source of supply and guiding all of them back and forth across the path of said material substantially from edge to edge thereof, means along said path of back and forth travel of the reenforcing-strand-presenting means arranged ahead of the final consolidating means to continuously receive and hold the strands in intimate contact with the material being reenforced.

2. In a machine of the character described, the combination of means for feeding material to be reenforced with an unwoven fabric layer consisting of a series of strands of spun yarn diagonally laid in two plies crossing each other, means moving to and fro in a substantially straight line for simultaneously carrying a plurality of said reenforcing yarn strands across the material to be reenforced, and means ahead of the final consolidating means arranged parallel to the path of said yarn carrying means adapted to continuously receive and press the yarn strands into intimate contact with the material to be reenforced.

3. In a fabric reenforcing machine, the combination of means for guiding and feeding the fabric longitudinally of the machine, a carrier mechanism moving to and fro in a substantially straight line for guiding a plurality of yarn strands from a source of supply and delivering them continuously into intimate contact with the fabric being reenforced each yarn strand reaching substantially from edge to edge thereof before reversing its direction, and a plurality of roller means adapted to continuously receive said yarn strands and directly press and hold them in intimate contact with the fabric as it passes longitudinally through the machine to the final consolidating means.

4. In a machine of the character described, the combination of means for feeding an adhesive coated material to be reenforced with an unwoven fabric layer consisting of a series of strands all diagonally laid just short of edge to edge thereof in two plies crossing each other, means moving to and fro in a substantially straight line for simultaneously carrying a plurality of said reenforcing strands across and just short of edge to edge of the material to be reenforced, and means arranged transverse the material to be reenforced which continuously receives said yarn strands and directly presses and holds them in contact with the adhesive coated face of the material as it passes to the final consolidating means.

5. In a machine of the character described, the combination of means for feeding an adhesive coated material to be reenforced with an unwoven fabric layer consisting of a series of strands of spun yarn diagonally laid in two plies crossing each other, means moving to and fro in a substantially straight line for simultaneously carrying a plurality of said reenforcing yarn strands across the material to be reenforced, each of said reenforcing yarn strands being laid across said material up to a narrow margin at each edge thereof which is left free from said yarn strands, and means arranged transverse the material to be reenforced which continuously receives said yarn strands and directly presses and holds them in contact with the adhesive coated face of the material as it passes to the final consolidating means.

6. In a machine of the character described, the combination of means for feeding material to be reenforced with an unwoven fabric layer consist-
